(57) **CLAIM**

We claim the ornamental design for a rotatable stud framing guide, as shown and described.

DESCRIPTION

FIG. 1 is a perspective view of a rotatable stud framing guide;

FIG. 2 is a back view thereof;

FIG. 3 is a front view thereof;

FIG. 4 is a top view thereof;

FIG. 5 is a bottom view thereof;

FIG. 6 is a left side view thereof;

FIG. 7 is a right side view thereof;

FIG. 8 is a perspective rotated view thereof; and,

FIG. 9 is a bottom rotated view thereof.

In the drawings herein, the broken lines depict portions of the rotatable stud framing guide that form no part of the claimed design.

1 Claim, 5 Drawing Sheets(56)
